1

Our invention relates to magnetic switching devices of the cartridge or plug-type, i. e. magnetically operated switches whose switch contact means are mounted within an insulating enclosure. Such devices are suitable for closing and opening electric circuits, the insertion of resistance, inductance or capacitance elements into such circuits, and for control, regulating or protective purposes in the various fields of electrical engineering.

It is an object of the invention to provide magnetically-operated switching devices of the above-mentioned type which, over those heretofore known, have a highly increased current-interrupting capacity at comparatively small dimensions so that the current density in the appertaining contact elements may reach unusually high values, for instance in the order of 50 amp./mm.², without causing excessive heating of the contact elements. It is also an object of the invention to provide switching devices of the type mentioned that lend themselves readily to performing diversified control operations and that, even when containing several cartridge-type units, require relatively little space as compared with known apparatus of similar performance. Other objects of the invention will be apparent from the following explanation and description.

According to the invention, in one of its aspects, we design and arrange the magnetically-controlled movable switching element, the appertaining magnet poles and stationary contacts within a cartridge-type housing in such a manner that the dissipation of heat from the switching element to the outside of the housing is mainly by heat conduction in the longitudinal direction of the element toward and into the stationary contacts. This makes it possible, with small dimensions of the housing, to achieve the above-mentioned high-current densities without excessive heating, provided the design and material are properly chosen, for instance, so that under steady-state conditions the voltage drop between the stationary contacts is at most about 0.15 volt.

In order to always secure a flow of conducted heat from the switching element to the stationary contact under avoidance of an excessive temperature of the element, it is also preferable to design the cartridge so that the switching element does not assume a temperature about 100° centigrade above that of the stationary contacts. Since, eventually, the heat is dissipated to the environment, the stationary contacts may be equipped with cooling surfaces such as ribs, vanes or fins. However, it is also possible to give the

2

stationary contacts ample dimensions, as regards size and heat conductance, so that they are capable of transferring the heat mainly by conductance to the amply dimensioned current supply conductors. If the current density in these conductors is so low that they heat up only moderately above the ambient temperature, these conductors are readily capable of dissipating the heat produced within the cartridge.

- 10 According to another feature of the invention, the switching element with its holding and biasing means, the magnetic pole pieces and also the stationary contacts are all mounted together to form a structural unit. This has the advantage that, for instance before inserting these parts into the housing, the switching element and the spring or other biasing means can be properly adjusted so that the subsequent assembling of the parts is facilitated.
- 15 20 The housing of switching devices according to the invention consists mainly of insulating material such as pressed material, a tube of wound-up material, or for more exacting requirements, of ceramic or vitreous material such as glass, quartz or the like. Since, generally, the magnetic control flux is applied by extraneous means and must enter into the switching device, the insulating housing is preferably designed as a tube whose ends are closed by members of such kind that there is virtually no weakening of the magnetic flux. The closure members may consist of thin plates of insulating material or metal. Preferable are closure members of ferromagnetic sheet material of at most 0.5 mm., especially about 0.1 mm. thickness which lie snug against the magnetic pole pieces in face-to-face relationship and have high specific electric resistance in order to keep eddy-current losses at a minimum.

40 The foregoing and other objects and features 45 of the invention will be apparent from the following description, in conjunction with the drawing in which Figure 1 illustrates an axial section through a switching unit according to the invention in association with the appertaining magnetizing yokes and current supply conductors, Figs. 2 to 4 show three other embodiments of switching units; and Fig. 5 illustrates a magnetic control device according to the invention which includes a plurality of switching units.

50 Referring to Figure 1, the magnetically controlled switching element of the device is denoted by 1. This element is mounted on an elastic shaft 2 which forms also the biasing spring for the switching element and tends to hold it in the illustrated position. The switching element is

disposed between two magnet pole pieces 3 and 4. The stationary contacts to cooperate with the switching element are denoted by 5 and 6. They are mounted in metallic sleeves 7 and 8 which are firmly secured to a tubular insulating enclosure 9. The torsion spring 2 is rigidly secured to this tube so that the switching element 1 is substantially thermally insulated from all other metal parts with the exception of the stationary contacts 5 and 6. The two ends of the insulating tube 9 are hermetically sealed by thin closure plates 10 and 11, for instance, of ferromagnetic metal. The magnetic yokes which supply the control flux ϕ are shown at 12 and 13. It may be necessary to cover the metallic closures 10 and 11 with insulating material for electrically insulating the cartridge from the yokes 12, 13. The additional insulation (not shown) should consist of a material of high insulating strength and good thermal conductivity, and its permissible temperature should be as high as possible. The current I_a to be controlled is applied to the stationary contacts by heavy conductive bars or buses 14 and 15. In the illustrated position of switching element 1, the current flows from bar 14 to the stationary contact 5, thence through the switching element 1 to the stationary contact 6 through which it enters into the bar 15. The switching element 1 is equipped with contact pieces 16 and 17. When the magnetic yokes 12 and 13 are energized to apply the control flux ϕ , the switching element 1 is rotated about its torsion shaft 2 in the counterclockwise direction thereby interrupting the current I_a .

The same switching device, however, may be operated so that the current I_a enters, for instance, through the yoke 13, the closure plate 11 and the pole piece 4 to the switching element 1 and leaves through pole piece 3, closure plate 10 and yoke 12. This current flow exists when the yokes 12 and 13 are magnetized so that an interruption of the current I_b is effected by terminating the magnetic excitation. In this modification, the stationary contacts 5 and 6 serve only as insulated stops, or the device may be employed so that the switching element acts as a make and break contact with the effect that the current I_a is switched in immediately after the interruption of the current I_b . For the last-mentioned mode of operation, contact pieces 17 and 18 are attached to the respective pole pieces, and contact pieces 19 and 20 are mounted on the switching element 1. The interior of the enclosure 9 may be filled with a gas 21 which, especially for high voltages, may have elevated pressure of 5 to 10 atmospheres. For certain purposes, however, the interior of the enclosure may be evacuated.

It will be recognized that when a circuit is completed by the switching element 1, the heat generated in the element is carried off substantially only by heat conductance from the switching element to the stationary contacts, that is, when the circuit for current I_a is closed, the heat flows from element 1 to contacts 5, 6 and the metal sleeves 7, 8 to the properly dimensioned conductor bars 14, 15. If the circuit for current I_b is closed, the heat is conducted from element 1 through the pole pieces 3, 4 to the yokes 12, 13 which are likewise amply dimensioned.

In the embodiment illustrated in Fig. 2, the switching element 1' extends horizontally and the stationary contacts 5' and 6' extend vertically and are disposed laterally with respect to the pole pieces 3' and 4'. The portions of the

stationary contacts that extend outside of the enclosure 9' are provided with cooling vanes 22 and 23 respectively. The pole surfaces of the pieces 3' and 4' are slanted so that aside from Maxwell's attractive forces, additional attractive forces are effective due to divergence in permeability. In order to prevent a change in the operating conditions, in particular a variation of the contact distance due to heating enclosure, the coefficient of thermal elongation of the pole pieces 3' and 4' and of the stationary contacts 5', 6' are so chosen relative to the coefficient of the housing 9' that the relative distances between these parts are substantially independent upon changes in temperature. In other respects, the performance of the device is similar to that shown in Fig. 1 and it will be understood that the special design features mentioned above in connection with Fig. 1 are likewise applicable to switching units of the type shown in Fig. 2.

If the switching devices are to cooperate with an impedance or other electric circuit element, such a circuit element according to another feature of the invention can be structurally combined with the cartridge-type housing. For instance, the housing may be equipped with a holding coil which magnetizes the pole pieces of the cartridge under control by the switching element once the pole pieces are sufficiently magnetized from an extraneous source of magnetic flux to initiate the operation. The magnetizing effect of the holding coil then maintains the switching element in the switched-in position and the switching element is permitted to return to its position of rest only when the current drops below a given small value, for instance 5% or 10% of the rated value. In order to combine such a holding coil with the device, the tubular housing may serve as a carrier for the coil. When using such a combination with direct current, the device closes or opens a circuit in response to a temporary and possibly very short control impulse and then causes the holding coil to produce a magnet field which maintains the pole pieces sufficiently energized to keep the circuit in the same condition after the termination of the control impulse until some other control effect occurs to interrupt the holding current. When using a holding coil with alternating current, the device can be used in such a manner that after the interruption of the controlling current, the magnetic energization is continued due to the effect of the controlled current until the controlled current approaches its zero passage. The switching function is then delayed accordingly and occurs only at an instantaneous value of the alternating current low enough to prevent damage due to arcs and undue contact consumption.

In cases where the switching unit is applied in order to insert a previously shorted resistor into an electric circuit, this resistor may be placed on and supported by the insulating housing of the switching unit in the same manner as mentioned above with reference to holding coils. Such a resistor combination has the advantage of affording minimum inductance of the resistance circuit, which is of advantage for the prevention of arcs at the switching-in moment. In a similar manner, the switching unit may be combined with an inductive or capacitive circuit element. For instance, the housing or insulating tube of the unit may form part of the casing for a condenser.

For many purposes, it is of advantage to con-

nect two or more switching elements in electric and magnetic parallel relation to one another. For instance, a relatively large number of switching elements, for instance 10 to 100 and more, can be placed into cartridge-type containers. It is sometimes also of advantage, especially for high voltages, to connect at least two switching elements electrically in series relation within a single housing. These switching elements may also be series-connected in magnetic respects. It is likewise possible to connect them electrically in series but magnetically in parallel.

The above-mentioned features and modifications are exemplified by the embodiment shown in Fig. 3. The device according to Fig. 3 has three switching elements 1' arranged in magnetic series relation between the pole pieces 3' and 4'. The insulating tube 9', which encloses the switching elements and is sealed at both ends by ferromagnetic plates 10' and 11', serves as a spool or carrier for a coil 24, for instance, designed as a holding coil. The magnetic pole pieces 3' and 4' serve as stationary contacts. Additional stationary contacts 25 are disposed between the switching elements in order to provide a definite position for the individual switching elements in the switched-in condition. However, the additional contacts 25 may be omitted and the switching elements designed for directly contacting one another. When a magnetic field impulse of sufficient strength is applied to the pole pieces, the switch elements 1' rotate counter-clockwise and close a circuit which includes the holding coil 24. The controlled current I then produces a magnetic field which maintains the circuit in closed condition regardless of whether or not the control flux from an extraneous source that initiated the performance continues.

In the embodiment according to Fig. 4, a switching unit 26, inserted between the yokes 27 and 27' is cooled by liquid 28 that serves also as a resistor. These yokes are electrically insulated from the magnetizing core 29 of the control coil 30 and form current conductors for the switching element as well as electrodes for the liquid. If the switching element is normally in open position, the resistance of liquid 28 is normally effective and is shorted when coil 30 is energized; or, if the switching element normally closes the circuit, the liquid resistance is normally shorted and becomes effective when coil 30 is energized.

If in devices according to the invention, as exemplified by the above-described embodiments, the electrically conductive parts, at which the opening and closing of the circuit occurs, consist of the customary contact materials, these materials insert an element of high magnetic reluctance, equivalent to an air gap, into the magnetic circuit. This reluctance element or "air gap" must have fairly ample dimensions in order to insure a safe electric contact even when the contact surfaces are partly consumed. The presence of such elements of high reluctance requires an increased amount of ampere turns for controlling the switching element and tends to reduce the contact pressure in the switched-in condition. Therefore, according to another feature of the invention, the stationary contacts and the corresponding contact pieces of the switching element, i. e. the parts denoted by 16, 17, 17', 18, 19, 20 in Fig. 1, are made of ferromagnetic material, for instance nickel, iron, cobalt and ferromagnetic alloys. It is essential that these

materials have high relative permeability of at least 50 to 100 up to the expected highest operating temperatures of the device.

If desired, the disappearance of the ferromagnetic condition of these materials when exceeding the so-called Curie temperature may be taken advantage of, for instance, in order to secure an automatic interruption of the current at an excessive temperature of the switching element. Nickel, having a Curie temperature of about 350° C., is well suitable for this purpose. The so-called Hausler alloys with Curie points down to about 70° C. are also applicable.

In order to prevent a change or deterioration of the contacts, especially those of ferromagnetic materials, at least the stationary contacts and the switching element are disposed within a chemically inactive atmosphere, for instance, nitrogen or hydrogen.

The magnetically active parts, that is, the switching element and the pole pieces, are preferably designed so as to have minimum magnetizing losses. Especially the hysteresis and eddy-current losses should be low if the switching operation is to be performed within intervals of extremely short duration. Therefore, these magnetic parts may be subdivided. For instance, these parts, especially at least the magnet pieces, may be composed of comminuted material.

Switching devices according to the invention are not only applicable for low currents and voltages, for instance, as customary in the communication and measuring fields, but they are likewise advantageous for power purposes. For applications of the latter kind, care should be taken that the elongation or expansion due to the considerable heating effects does not affect the functioning. To this end, the thermal coefficients of expansion of the cooperating parts of the switching cartridge should be chosen in proper relation to one another, for instance, as explained above with reference to Fig. 3. The disturbing effect of thermal expansion can be minimized in a simple manner if the contact surfaces and pole surfaces are designed so that the tangential planes in the points of engagement of the contacts, as well as the pole surfaces, extend in parallel to the main direction of thermal expansion of the switching unit or cartridge. In general, this is tantamount to locating the switching element with its longitudinal axis substantially in parallel to the longitudinal axis of the switching unit in accordance with the embodiments of Figs. 1 and 3.

In order to increase the current-carrying capacity, devices according to the invention may be cooled by a suitable cooling agent. The application of artificial cooling is especially simple if the cartridges or housings are hermetically sealed in accordance with the illustrated embodiments. This permits using a gaseous medium, for instance a flow of air, for cooling purposes. However, the switching units may also be arranged within a stationary or flowing liquid, for instance, in oil or in a water-glycol solution of sufficiently small conductivity. If desired, the cooling agent may serve as a resistor to be controlled by the switching device. In the latter case, the liquid preferably consists of an electrolyte of the desired conductivity. The appertaining electrodes should be designed so that the current density remains within permissible limits.

A plurality of switching units or cartridges according to the invention may be connected in parallel, in series, or in mixed circuit arrange-

ments. In such electric parallel connections, it may be useful, for maintaining a balanced load distribution until the moment of complete interruption, to connect an inductance coil in series with each unit. This coil, if desired, may be combined with the cartridge housing to a structural entity in a manner similar to the embodiment shown in Fig. 3. If units with holding coils are employed, such an inductance coil may consist of at least part of the holding coil.

Switching devices as exemplified by the above-described embodiments may be used as individual apparatus or, according to another feature of the invention, several switching units or cartridges appertaining to electrically separate current paths are subjected to a common magnetic control flux. For instance, a single control coil may produce the controlling magnetic flux for the plurality of cartridges, while the magnetic return path extends through the individual units. As a rule, a magnet core surrounded by the control coil represents the source of the magnetic control flux, this source having a small magnetic reluctance as compared with that of the several switching units controlled thereby. However, the control coil may also immediately act upon one of the cartridges, while other cartridges form the magnetic return path or part thereof. If desired, more than one control coil may be provided to jointly act on the magnetically associated cartridges.

In devices of the just-mentioned type, the switching units or cartridges may be assigned for response to respectively different values of an electric current. To this end, the different units may be rated to respond to respectively different critical currents. For the same purpose, however, several switching units may have the same critical current value while means extraneous to the units proper are provided to make the equally rated units respond to respectively different current values. Such a different response of substantially equally rated units is obtained, for instance, by inserting magnetic resistance or reluctance into the magnetic circuit of one or several of the units. Different reluctance in the magnetic circuit can be obtained by providing air gaps of different width. For certain purposes, a simultaneous response of several or all switching units of such a multiple device is desirable.

In general, the different units or cartridges appertaining to the device are magnetically parallel-connected in order to maintain the controlling ampere turns at a minimum. There are cases, however, in which it is preferable to arrange the cartridges at least partly in a magnetic series connection.

Depending upon the operating conditions, the magnetic control flux is unidirectional or variable. When operating with alternating current, the control flux can be prevented from dropping to zero by providing two or more phase-displaced control fluxes. These fluxes may stem from separate current sources. In most cases, however, a phase-displaced flux is more simply obtained with the aid of short-circuit windings. Such a winding may be common for a number of switching units, although it is also possible to assign a short-circuited winding to each.

For many cases of application, the switching device for the main current is advantageously combined with an auxiliary switching device for the control currents, the auxiliary device being also subject to the control flux. It may be of ad-

vantage to equip the auxiliary switching device also with switching units which, as a rule, may have smaller dimensions and may be rated for a smaller switching capacity than those of the main device.

If the current in one of the separate circuits to be controlled by the switching device is above the current value permissible for one switching unit, two or more units may be electrically parallel-connected. For operating with high voltages, it may be similarly of advantage to electrically series-connect two or more units.

The above-mentioned features relating to a multiple unit device according to the invention are exemplified by the embodiment illustrated in Fig. 5. The core 31 of the magnetic field structure shown in this figure is equipped with a control coil 32 and also with a short-circuited winding 32', which permits energizing the control coil 32 with alternating current while preventing the magnetic control flux induced in core 31 from dropping to zero due to the current zero passages of the energizing control current. The core 31 is joined with two yokes 33 and 34. The yokes 33 and 34 extend in parallel to each other and form extended pole surfaces between which three cartridge-type switching units 35, 36 and 37 are inserted. As apparent from the sectional illustration of cartridge 35, each cartridge has two magnet pole pieces 38 and 39, a movable switching element 40, and an insulating tubular body 41. In detail, the cartridges are designed in accordance with the features of the invention represented in Figs. 1, 2 and 3. Each cartridge is shown to be equipped with a holding coil 42, 43 and 44 respectively, arranged on the insulating enclosure of the cartridge, as explained in the foregoing with reference to Fig. 3. The magnetic field system is equipped with auxiliary yokes 47 and 48 for controlling an auxiliary switching device denoted, as a whole, by 45. The auxiliary device is composed of three switching cartridges, all denoted by 46. The switching cartridges 35, 36 and 37 are electrically insulated from the yokes 33 and 34 by insulating strips 49 and 50.

The switching device according to Fig. 5 may be applied for the following purpose. If the control coil 31 is energized by a control current of a given value i_1 , the switching cartridge 35 is supposed to respond and to close its circuit so that a current I_1 flows in the appertaining circuit connections. At the same time, one of the auxiliary cartridges 46 is to operate. If the controlling current in coil 32 is increased to a given value i_2 , the current I_2 previously flowing in the circuit of cartridge 36 is to be interrupted for instance, and this occurrence is to be transmitted to a central station by the response of an appertaining control switch. When the current in coil 31 assumes a still higher value i_3 , the current I_3 is supposed to be switched-in by the cartridge 37. It will be understood from the explanation given in the foregoing that the just exemplified mode of operation is readily achieved by designing the switching elements of cartridges 35 and 37 as make contacts and the switching element of cartridge 36 as a break contact, and by rating the critical currents of the three cartridges correspondingly.

This example will show that multiple switching devices according to the invention lend themselves readily for a large variety of applications. For instance, such a device can be applied as an alternating-current relay, especially for multi-

phase current, with the result that complicated relay control schemes can be carried out with simplified relay devices that require considerably less space than the separate relays heretofore customary for such purposes. For instance, if in a control system a number of separate circuits are to be switched simultaneously, all these circuits can be controlled by respective switching units or cartridges which are subjected to the control flux of a single control coil. For starting schemes, a multiple device according to the invention may be used to perform a given sequence of control actions in response to a progressive change of the control current. Similar advantages are obtained in remote control and measuring systems, for regulating purposes and also for rectification, inversion, or other translation of electric current or voltage in which a controlled switching or commutation between circuits is required. An essential advantage of such devices lies in the fact that a virtually unlimited variety of control actions can be performed with small control energies and that the particular requirements can readily be satisfied by selecting proper combinations of control coils and switching units.

It will be understood from the foregoing disclosure by those skilled in the art that the invention permits various alterations and modifications and can be embodied in devices other than those specifically shown and described without departing from the gist of the invention and within its essential features as set forth in the claims attached hereto.

We claim:

1. A switching device, comprising an insulating housing, two magnet pole pieces having respective pole faces spaced from each other within said housing, said pole pieces extending from within to substantially the outside of said housing, a magnetizable rigid switching member pivoted at its center between said pole pieces for rotational movement toward said two pole faces and away therefrom respectively, spring means for biasing said member away from said pole faces, and two stationary contact structures extending from without to within said housing and having in said housing respective contact faces bridged by said member in one of said positions, said contact structures having at all points between said contact faces and the outside of said housing a conductive cross section larger than that engageable by said member.

2. A switching device, comprising an insulating tubular housing, two magnet pole pieces disposed in the two axial ends respectively of said housing so as to substantially close said housing ends, said pole pieces being axially spaced from each other and having two respective pole faces within said housing and two outer faces at said axial ends respectively of said housing, a magnetizable rigid switching member disposed in said housing between said pole pieces and pivotally connected with said housing for angular movement toward and away respectively from said pole faces, said member extending substantially in the axial direction of said housing, biasing means for normally holding said member away from said pole faces, and electric contact means including said member to be closed and open depending upon the position of said member.

3. A switching device, comprising an insulating tubular housing, two rigid magnetic pole pieces attached to said housing at the respective ends thereof and having respective pole faces spaced

from each other within said housing, said pole pieces being magnetically and electro-conductive-ly accessible outside said housing, a rigid switching member revolvably mounted in said housing between said pole pieces so as to be movable between two positions toward said pole faces and away therefrom respectively, said member having biasing means tending to hold it away from said pole faces and consisting substantially of ferromagnetic material to be movable toward said pole faces when magnetized thereby, and two rigid parts of electric contact material integral with said respective pole pieces and electrically engageable by said member to be bridged thereby.

15 4. A switching device, comprising an insulating housing, two magnet pole pieces attached to said housing at opposite sides respectively and having respective pole faces within said housing, two stationary rigid contact structures extending from without to within said housing and having respective contact faces within said housing, an elongated rigid and magnetizable switching member pivoted about its center within said housing between said pole pieces and movable between

20 25 30 35 40 45 50 55 60 65 70 75 80 85 90 95

two angular positions, said member having a pair of faces engageable with said pole faces when said member is in one position and having a pair of faces engageable with said contact faces when said member is in the other position, said member being biased toward said other position and magnetically controllable by said pole pieces to move to said one position, all said faces extending substantially parallel to the longitudinal direction of said member.

5. A switching device, comprising an insulating housing, two ferromagnetic and electrically conductive pole structures insulated from each other and extending from without to within said housing, said structures having respective pole faces spaced from each other within said housing and having respective portions accessible at the outside of said housing for supplying magnetic flux and electric current, contact pieces of electrically good conductive material disposed on said respective pole faces, a magnetizable and electrically conductive armature member disposed within said housing and magnetically movable toward said pole faces, said member when so moved being in electric bridging engagement with said two contact pieces, spring means disposed in said housing, said armature member being rigid throughout and being mounted on said spring means, said spring means having relative to said member a biasing force directed away from said pole faces for disengaging said member from said structures and being the only mechanical support of said member.

6. A switching device, comprising an insulating housing, two ferromagnetic and electrically conductive pole structures insulated from each other and extending from without to within said housing, said structures having respective pole faces spaced from each other within said housing and having respective portions accessible at the outside of said housing for supplying magnetic flux and electric current, each of said pole structures having a piece of electric contact material disposed on said pole face in face-to-face contact therewith, a rigid and electrically conductive armature member movably disposed in said housing, biasing spring means connected with said member to bias it away from said pole faces, said member being magnetically movable toward said pole faces due to said flux and being engageable

with said two pieces of contact material to electrically bridge said structures.

7. A switching device, comprising an insulating housing, two magnetically and electrically conductive structures extending from within said housing to the outside of said housing and having respective faces spaced from each other within said housing, said structures being electrically insulated from each other and being accessible from the outside of said housing for passing magnetic flux and electric current through said structures, a magnetizable and electrically conductive switching member disposed in said housing and being movable into bridging engagement with said two faces and away therefrom to electrically interconnect and disconnect said two structures, a biasing spring connected with said member in said housing for biasing said member away from said faces, each of said structures having at all points between said face and the outside of said housing an electrically conductive cross section larger than the area of contact engagement with said member.

8. A switching device, comprising an insulating housing, two magnetically and electrically conductive structures extending from within said housing to the outside of said housing and having respective pole faces spaced from each other within said housing, said structures being electrically insulated from each other and having respective portions magnetically and electrically accessible from the outside of said housing for passing magnetic flux and electric current through said structures, a magnetizable and electrically conductive member being rigid throughout and being disposed in said housing, a biasing spring means connected with said member for biasing it away from said two pole faces, said member being mechanically supported only by said spring means and being movable due to said flux into bridging engagement with said two structures of said respective pole faces to then electrically interconnect said structures, each of

said structures having at all points between said pole face and the outside of said housing an electrically conductive cross section larger than the area of contact engagement with said member.

9. A switching device, comprising a plurality of individual devices according to claim 7 connected in magnetic and electric parallel relation to each other and having a common magnetic field structure outside of said respective housings and a common control coil on said field structure, said field structure having two yoke portions in magnetic engagement with said respective two structures of each of said individual devices.
